UNITED STATES PATENT OFFICE

2,411,343

SPRAYING APPARATUS

Henry Singer, Honolulu, Territory of Hawaii

Application May 24, 1944, Serial No. 537,150

2 Claims. (Cl. 261—30)

1

This invention relates to a spraying apparatus, and it is an object of the invention to provide an apparatus of this kind especially designed for use for the diffusion of a liquid in the form of a whirling mist.

Another object of the invention is to provide a device of this kind having novel means for effectively diffusing a liquid insecticide and to also provide an apparatus of this kind whereby the liquid is discharged in the form of a mist.

It is also an object of the invention to provide an apparatus of this kind constructed in a manner to permit the same, when not spraying, to be employed to advantage as a lamp or as a fan.

It is another object of the invention to provide an apparatus of this kind which can be easily knocked down and reassembled to facilitate cleaning and oiling when necessary.

Furthermore, the invention has for an object to provide an apparatus of this kind wherein the liquid is discharged or diffused upwardly in the form of a mist and wherein provision is made for regulating or controlling at will the upward throw of the mist.

The invention consists in the details of construction and in the combination and arrangement of the several parts of my improved spraying apparatus whereby certain important advantages are attained, as will be hereinafter more fully set forth.

In order that my invention may be better understood, I will now proceed to describe the same with reference to the accompanying drawing, wherein:

Figure 1 is a view partly in vertical section and partly in elevation illustrating a spraying apparatus constructed in accordance with an embodiment of the invention;

Figure 2 is a view taken substantially on the line 2—2 of Figure 1; and

Figure 3 is an enlarged fragmentary detail view taken substantially on the line 3—3 of Figure 2.

As disclosed in the accompanying drawing, the apparatus is illustrated in the general simulation of a torchiere type floor lamp and wherein is provided a hollow base member 1 from the central portion of which extends a tubular upright or post 2 in communication therewith. The base 1 has in communication therewith a suitably positioned drain 3.

Provided at the upper extremity of the upright or post 2 is a bell-like member 4 which constitutes a basin and with which the upright or post 2 communicates. The upper marginal portion of this basin 4 is surrounded by the upwardly and

outwardly inclined shell or apron 5 of desired inclination and preferred major diameter.

At substantially the axial center of the apron 5 is an annular support or platform 6 of a major diameter slightly in excess of the diameter of the upper open face of the basin 4 but considerably less than the major or upper diameter of the apron 5.

Radiating from this support or platform 6 and disposed outwardly therefrom are the relatively narrow arms 7 terminating in the depending feet 8 which are suitably anchored, as at 9, to the apron 5, or skirt as it may also be called, adjacent the upper or outer margin of such apron or skirt 5. These feet 8 are of such dimensions as to position the support or platform 6 a desired distance above the upper or outer margin of the apron or skirt 5.

The lower portion of the basin 4 and at desired points circumferentially therearound is provided with the inwardly disposed buttons 10 upon which is rested an electric motor M of any preferred type, with the power take-off shaft 11 of such motor extending vertically upwardly and positioned at the axial center of the central opening 12 of the support or platform 6.

Positioned upon the support or platform 6 is a container C, herein disclosed as substantially semi-spherical in form, and which is provided at the axial center of its flat bottom wall 14 with a depending discharge nozzle 15 which passes snugly through the central opening 12 of the support or platform 6.

The lower portion of the nozzle 15 is telescopically received within the upper open extremity of an elongated cylindrical chamber member 16. This chamber member 16 has a relatively heavy bottom wall 17 which is mounted upon the upper end portion of the power take-off shaft 11 and fixed thereto, by the securing means 18, for rotation therewith.

Associated with the container C is a compression pump 19, herein disclosed as of a hand type, while the upper end of the container C is provided with a filling opening 20 adapted to be closed in a conventional manner by the cap 21.

The nozzle 15 is intersected by a plate 22 provided at its central portion with a valve casing 23 open at the top and bottom and in which is mounted a rotary valve 24 of a spigot type and which is operated by a stem 25 extending through the wall of the nozzle 15 and rotatably supported, as at 26, by a marginal portion of the apron or skirt 5. The outer extremity of the stem 25 carries a knurled head 27 or the like whereby

the valve 24 may be adjusted at will to either open or closed position.

Carried by the upper portion of the member 16 and radiating outwardly therefrom are the fan blades 28 of a conventional type and of a desired number and which, upon rotation of the member 16, serve to create an upward stream of air.

Carried by each of the blades 28 and underlying the same is a pipe line 29, one end portion of which, as at 30, extends within the chamber member 16 while the opposite end portion of the pipe line 29 extends through the outer portion of the blade 28 and a slight distance thereabove and said outer extension carries a mist diffusing or fog sprayer 31. This sprayer 31 may be of any type preferred.

Suitably arranged upon the skirt or apron 5 at desired points therearound are the electric lighting elements 32 of a conventional type, the conductors 33 therefor extending downwardly of the post 2 and out through a wall thereof at the lower portion of said post. This conductor is adapted for connection with a suitable source of electric energy. Interposed in the conductor and arranged exteriorly of the post 2 is a controlling switch 34.

The motor M is also in proper electrical connection, as indicated at 35, with the conductor cable and such connection 35 is under the control of a conventional switch 36. It is believed to be obvious that the motor can be caused to operate independently of the lighting elements 32 and vice versa, so that, when desired, the apparatus herein disclosed can be employed as a fan or as a lamp independently of any spraying function.

The liquid, such as an insecticide, is placed within the container C and placed under proper pressure by the action of the pump 19. With the valve 24 open, the liquid will enter the lower portion of the chamber member 16 and under such pressure will be forced out through the pipes 29 and nozzles 15, so that effective diffusing of the liquid in a mist or fog will be obtained. This diffusing of the mist or fog will also be further facilitated by placing the member 16, together with the blade 28, in rotation. All liquid that may drop or gravitate upon the apron or skirt 5 will drain into the basin 4 and down through the post 2 into the hollow base member 1, whereby such liquid may be readily recovered through the drain 3.

It is believed to be obvious that with the apparatus as herein disclosed, the mist or fog is thrown upwardly and that such upward throw of the mist or fog will be dependent upon the air compression within the container C. Obviously

the greater such compression, the higher the throw of the mist or fog. During the time the mist or fog is being discharged, it is believed to be readily understood that the fans will create such air draft as to materially facilitate the desired diffusion and as the lighting elements 32 are located out of the path of rotation of the blades 28, such elements may be employed, if desired, during the period of diffusion. It is also believed to be obvious that when either the fan blades 28 or the lighting elements 32 are being used collectively or separately, the valve 24 should be closed unless, of course, the spraying operation may also be desired.

From the foregoing description it is thought to be obvious that a spraying apparatus constructed in accordance with my invention is particularly well adapted for use by reason of the convenience and facility with which it may be assembled and operated.

What is claimed is:

1. A device of the character stated comprising a hollow base having a tubular standard leading upwardly therefrom, said standard at its upper end carrying and opening into the lower part of a basin-like receptacle having an upwardly and outwardly flaring apron-like edge extension, a motor unit supported within said basin and having an upwardly directed shaft, a chambered body supported upon said shaft for rotation and having an open upper end, a plurality of tubes each having an end opening into the chambered body, the tubes extending radially outwardly from the body, a spray nozzle at the outer end of each tube directed upwardly and outwardly, the overall diameter of said apron being materially greater than the distance between diametrically oppositely positioned nozzles, a fluid receptacle supported above the center of the basin, a fluid conducting conduit leading from the receptacle into the chambered body and closing the said open end of the body, and a control valve within the conduit for controlling the flow of fluid from the receptacle into the chambered body.

2. A structure of the character stated in claim 1, with a platform disposed above the chambered body and having an opening through which said conduit passes, the receptacle being supported upon the platform, and radial arms forming a part of the platform and extending outwardly and connected at their outer ends with the apron for supporting the platform and receptacle above the motor and chambered body, said chambered body and nozzle carrying tubes being rotatable beneath the arms and the apron.

HENRY SINGER.
